UNITED STATES PATENT OFFICE

161,431

ADJUSTABLE SHOWER HEAD ATTACHMENT

William H. Derbyshire, Miami, Fla.

Application July 10, 1950, Serial No. 11,038

Term of patent 7 years

(Cl. D4—3)

To all whom it may concern:

Be it known, that I, William H. Derbyshire, a citizen of the United States, residing in Miami, Florida, have invented a new, original, and ornamental Design for an Adjustable Shower Head Attachment, of which the following is a specification, reference being had to the accompanying drawing, forming a part thereof.

Fig. 1 is a top plan view of an adjustable shower head attachment showing my new design;

Fig. 2 is a side elevational view of the attachment; and

Fig. 3 is a front elevational view of the attachment.

I claim:

The ornamental design for an adjustable shower head attachment, as shown.

WILLIAM H. DERBYSHIRE.
